UNITED STATES PATENT OFFICE.

CROMWELL A. B. HALVORSON, JR., OF SAUGUS, MASSACHUSETTS, ASSIGNOR TO
GENERAL ELECTRIC COMPANY, A CORPORATION OF NEW YORK.

FLAME ARC-LAMP.

1,118,414.

Specification of Letters Patent.

Patented Nov. 24, 1914.

Application filed December 27, 1909. Serial No. 534,954.

To all whom it may concern:

Be it known that I, CROMWELL A. B. HALVORSON, Jr., a citizen of the United States, residing at Saugus, county of Essex, State 5 of Massachusetts, have invented certain new and useful Improvements in Flame Arc-Lamps, of which the following is a specification.

This invention relates to electric arc 10 lamps, and its object is to provide a lamp of the flaming or luminous arc type which will burn for a much longer time than the ordinary arc lamp, and therefore require less attention from the trimmers.

15 A further object is to simplify the mechanism and secure an even and automatic feeding of the electrodes.

My lamp is of that type in which the electrodes are inclined downwardly toward 20 a common meeting point just below an economizer. The arc is struck by separating the tips of the electrodes in a lateral direction. The electrodes are suspended from holders which slide freely on inclined 25 guide rods and hung on the arms of a vertically-movable traveler.

The positive electrode comprises two electrode members converging toward each other, each member comprising one or more 30 carbons, all of the positive carbons being located in the same plane. The feed is regulated by the burning away of the contiguous tips of the adjacent carbons of the two positive electrode members. The negative 35 carbons are preferably arranged parallel with each other in a plane inclined toward that of the positives.

In the accompanying drawings, Figure 1 is a perspective view of my lamp taken on 40 the side of the negative electrode; Fig. 2 is a perspective taken on the side of the positive electrode; Fig. 3 is a side elevation showing a portion of the arc-striking mechanism; Fig. 4 is a side view at right angles 45 to Fig. 3; Fig. 5 is a plan view with the electrodes in section, showing the arc striking slide; Fig. 6 is a side elevation of said mechanism in the position it occupies when the arc is struck, and the lamp is burning; 50 Fig. 7 is a bottom plan view of the economizer showing the lower ends of the electrodes; Fig. 8 is a perspective view of the top plate 4 and the mechanism located im-

mediately above the same for moving one set of electrodes laterally, and Fig. 9 is a 55 side elevation showing the frame of the lamp.

The frame of the lamp comprises a canopy 1, below which is supported a top plate 2. Two parallel hollow columns 3 extend 60 downwardly from the canopy to the platform 4, which is annular to afford a support for the economizer 5, whose flange 6 rests on the platform. The hollow columns serve as chimneys or flues to carry 65 off the fumes of the arc from the chamber in the economizer. A central vertical post 7 extends from the top plate downwardly toward the platform, as do also three guide rods 8 grouped around the center post and 70 converging at the lower ends, where they are secured in a cross bar 9 attached by arms extending therefrom to the chimney columns. On the center post 7 slides a traveler consisting of a block 10 having a 75 central hole fitting the post easily. Three arms 11 project radially from this block, terminating in proximity to the guide rods. On each arm is mounted a carrier 12 which moves along and is guided by one of the rods 80 and is, at the same time, adapted to move freely in and out along said arm. From each carrier, and suitably insulated therefrom depends a holder 13 for the electrodes.

I prefer to support two or more carbons in 85 each holder, thus constituting my lamp a multiple carbon lamp; but if there is only one carbon in each positive electrode holder, the negative electrode holder would carry two carbons, and the lamp would still be a 90 multiple carbon lamp. In the drawings I have shown four positives and four negatives, but this number is not essential and may be varied at will. Assuming, however, that this is the number selected for use, the 95 four positives will be divided equally between two of the holders, while the four negatives will be all held in the third holder; the positives being arranged in one plane and the negatives in another plane inclined 100 to that of the positives.

The lower ends of all the electrodes pass through apertures in guide plates resting on the top of the economizer. One of these plates—preferably the one for the positives—is stationary, while the other is mov-

able in a horizontal plane toward and away from the stationary one. The two pairs of converging positive carbons 14 pass through the apertures in their guide plate 15 and the tips of the adjacent carbons in the two pairs abut in the chamber of the economizer. As both pairs are connected to the single traveler 10, neither pair can slip past the other, and thus their arcing ends remain stationary, and serve to support the traveler and the four negative carbons 16 suspended therefrom and depending through the apertures in the movable guide plate 17. The downward feed of both electrodes thus depends upon the burning away of the abutting tips of the two adjacent carbons of the two positive electrode members.

The movable guide plate 17 is preferably provided with a pair of upwardly-turned ears 18 between which is journaled a roller 19 to support the plate on the upper surface of the economizer and facilitate its movements. The side edges of the plate are turned upwardly to stiffen it, and are connected by arms 20 with downwardly-extending rock arms 21 on a shaft 22 journaled in a frame 23 rising from the platform 4. A lever 24 is connected with one of said arms by means of which the movable guide plate can be slid to and fro over the economizer and thus carry the tips of the negative electrode away from and toward the positive, in a horizontal direction. A lifting rod 25 is pivoted to the lever and connects at its upper end with the plunger cores 26 of the lamp magnets 27. A dash pot 28 dampens the movements of said cores, as usual.

When the lamp is not burning, the cores are down and the tips of some or all the carbons are in contact, as shown in Fig. 3. As soon as the lamp circuit is closed, the current flows from the positives to the negatives, and at the same time the magnets lift the cores and the lifting rod and the lever 24, thereby sliding the guide plate 17 to one side and separating the tips of the negatives from those of the positives, as shown in Fig. 6; thus drawing the arc. Should the current fail, the cores will drop and draw the negative carbons against the positives, ready to start a new arc as soon as the current comes on again.

By using multiple sets of electrodes, for example three as illustrated, each carbon in one set standing opposite a corresponding carbon in the other, the arc is enabled to shift from one pair of positive and negative carbons to another depending upon the relative distances between the several pairs of carbons, the arc naturally seeking the two which are nearest together. In this way, the four pairs herein shown by way of example are burned intermittently but not simultaneously, so that the life of the

lamp is four times as long as that of one having but a single pair of carbons. By multiplying the number of carbons, which can be readily done by changing the holders and the guide plates to correspond, the lamp may be made to burn for quite a long time without requiring the services of a lamp trimmer. The advantages of this for municipal lighting are apparent.

For convenience of description, I have termed the carbons 14 positive and those numbered 16 as negative; but it is evident that the polarities may be reversed, if desired.

In the foregoing description I have spoken of the rods which compose the electrodes as "carbons," but it is manifest that one or both electrodes may be composed of rods of other suitable material, the term "carbon" being in this case intended to include any such material.

What I claim as new and desire to secure by Letters Patent of the United States, is,—

1. In an arc lamp, a group of two or more parallel carbons constituting an electrode of one polarity, arranged in one plane; two electrode members each of which comprises one or more carbons of the opposite polarity located in another plane which converges toward the plane of said group, the two electrode members converging toward and abutting against each other, and means for causing all of said carbons to move along their axes in step.

2. In an arc lamp, two electrodes, one composed of a plurality of parallel carbons arranged with their tips in a straight line and the other composed of two electrode members each comprising one or more carbons, the two members being inclined toward and abutting against each other in the common plane of said members and with their tips also in a straight line, the two lines being parallel, and means for causing all of the carbons to move along their axes in step.

3. In an arc lamp, a group of two or more parallel carbons of one polarity arranged in one plane, two electrode members each of which comprises one or more carbons of the opposite polarity, all located in another plane which converges toward the plane of said group, the two electrode members of one polarity converging downwardly toward and abutting against each other, and means for mechanically connecting together all of the carbons.

4. In an arc lamp, the combination with one set of parallel carbons of one polarity all in one plane, of another set of carbons of the opposite polarity equal in number to those in the first set and all in another plane and divided into two electrode members inclined toward and abutting against each

other, the planes of the two sets of carbons converging downwardly and each electrode member comprising one or more carbons, means for moving one set of carbons laterally away from the other set in order to strike the arc, and means for moving all of said carbons along their axes in step.

In witness whereof, I have hereunto set my hand this seventeenth day of December, 1909.

CROMWELL A. B. HALVORSON, Jr.
